VACUUM CLEANER

Benjamin S. Foss, Brookline, Mass., assignor to
 B. F. Sturtevant Company, Hyde Park, Mass.,
 a corporation of Massachusetts

Application June 18, 1934, Serial No. 731,024

13 Claims. (Cl. 15—257)

The present invention relates to vacuum cleaners.

Vacuum cleaners as now manufactured for domestic use are of two general types, a traveling cleaner supported partly or entirely on wheels and caused to travel back and forth over the carpets, rugs, etc., to be cleaned, and a hand cleaner of relatively small size held in the hand of the operator for cleaning upholstery, draperies and the like.

While the suction developed by many of the cleaners of the hand type is adequate for cleaning rugs and carpets, the use of such a cleaner directly upon floor coverings is too difficult and tiresome for the operator, necessarily involving a bending or stooping over or a kneeling upon the floor. It is the object of the present invention to provide means for converting at will a hand cleaner into a traveling cleaner for use in cleaning rugs in the same manner and with the same ease and facility as with the larger and more cumbersome types designed exclusively for such work. Thus advantage may be taken of low first cost, light weight, and ease of manipulation of the hand cleaner, and both types of cleaner made available with only a single cleaning unit.

With this object in view, the present invention comprises briefly a carriage having wheels and a guiding handle upon which a hand cleaner may be easily and quickly mounted for use as a traveling cleaner or from which it may be as easily removed to be used as a hand cleaner. The invention also comprises certain novel features of construction, combinations and arrangements of parts hereinafter described and particularly defined in the claims.

In the drawing, Fig. 1 is a side elevation of a carriage embodying the invention in what is now considered the preferred form with a hand type vacuum cleaner mounted thereon; Fig. 2 is a sectional side elevation of the lower part of the carriage with the cleaning unit removed; Fig. 3 is a rear elevation of the same on a larger scale; Fig. 4 is a front elevation of the handle; Fig. 5 is a section of the same on line 5—5 of Fig. 4; Fig. 6 is another section on line 6—6 of Fig. 4; Fig. 7 is a detail view of the strap hinge construction; and Fig. 8 is a detail sectional view showing the method of retaining the wheels on the axle.

The hand vacuum cleaner or cleaning unit shown in Fig. 1 may be of any usual type having a substantially cylindrical horizontal motor casing 8 and a fan casing 10, the inlet of which

comprises the cleaning nozzle 12, and to the outlet of which is attached the usual bag 16. The cleaner is provided with an electric cord 18, and the small handle 20 suitable for use in operating the device as a hand cleaner. A switch 21 is provided for controlling the operation of the motor.

According to the present invention, the cleaner may be mounted in a wheeled carriage to permit its use in the same manner as the conventional larger traveling cleaner. This carriage comprises a supporting plate 22, the major portion of which is of generally cylindrical form to partially embrace the motor housing 8. The plate is provided with rubber buttons or spacers 24 to protect the cleaner and also to space it slightly from the plate for purposes of ventilation.

The motor housing is secured to the plate by means of straps 26 and 28 hinged to the plate. As shown in Figs. 2 and 3, the strap 26 is provided at the end with ears 30 on which is pivoted a looped wire 32. Similarly pivoted to the strap 28 is a tongue 34 adapted to enter the loop and having a toggle cam 36 to engage the end of the loop and thereby to tighten the straps about the motor housing when the tongue 34 is moved to the full-line position of Fig. 3. As shown in Fig. 7, each hinge 38, by which the strap is connected to the plate 22, has the middle section 39 of less width than the strap and the end sections formed on the plate are provided with offsets 40, so that the straps cannot swing outwardly farther than indicated in the dot-and-dash lines of Fig. 3.

The rear portion of the plate 22 departs from the cylindrical shape of the front portion and terminates in a curved portion 42 surrounding an axle 44 and freely movable thereon. The propelling and guiding handle 45 is formed of two strands of wire twisted together, the strands being separated at the lower end of the handle to form a yoke 46 having its ends 47 curled around the axle adjacent to the part 42 of the plate, as shown in Figs. 2 and 3. Above the yoke portion, the wires are welded and twisted, as indicated at 48 and 50, for purposes of rigidity and strength.

The entire handle may be made of a single piece or loop of wire, but in order to permit disassembly for shipping, the handle is preferably made in two sections, as shown in Fig. 4, the two wires forming the lower portion terminating in a ferrule 52 fixed thereon, see Figs. 4 and 6, and the ends of the single piece of twisted wire 54

- which forms the upper portion of the handle being received in the ferrule. The lower ends of the wire 54 are welded at 55 and are tapped to receive a screw 56 passing through the ferrule.
- 5 A two-part wooden grip 58 is riveted to the top of the handle and the upper end of the handle terminates in a loop 60 convenient for hanging the carriage on a hook. Immediately below the grip 58, a spring clip 62 is welded between the 10 wires for the purpose of supporting the electric cord 18, as shown in Figs. 1 and 5.
- A pair of wheels 64 are mounted on opposite ends of the axle 44, the wheels being spaced from the ends of the handle by washers 66. The 15 wheels are retained on the axle by any suitable means, illustrated in Fig. 8 as snap rings 68 received in annular grooves of the axle 44.
- It will be seen in Fig. 3 that the rear portion of the plate 22 is flared outwardly at both sides 20 to lie directly in front of the handle, as indicated at 70, serving as a stop whereby the handle has provision for limited swinging movement with respect to the cleaner carriage, both upwardly and downwardly. As shown in Fig. 2, the handle 25 is permitted to move in a counter-clockwise direction until the yoke portions thereof engage with the upper surface of the flared portion 70 of the plate when the handle will be slightly inclined forwardly. It is also permitted to move in a 30 clockwise direction until the ends of the wire engage the under surfaces of the flared portions 70. This permits the free normal swinging movements of the handle in pushing and pulling the cleaner over the floor, at the same time providing for holding the handle upright and also for lifting of the nozzle from the floor when the handle 35 is lowered.
- To mount the cleaner in the carriage, it is 40 simply necessary to place the cleaner nozzle and the wheels on a flat surface and then to clamp the cleaner in place on the plate 22 by means of the straps 26 and 28. When it is desired to use the cleaner as a hand cleaner, it is easily disconnected from the carriage.
- 45 The hand cleaner with the carriage of the present invention is particularly suitable for small homes and apartments in which the floor area is fairly small and storage space is at a premium. The invention is, however, frequently useful in 50 large homes because, although the hand cleaner nozzle is somewhat smaller than that of the ordinary traveling cleaner, the labor and time involved in cleaning a large surface may be no more, than with a large cleaner, considering the saving 55 of effort in moving the cleaner over the surface and in carrying it up and down stairs. Furthermore, the hand cleaner is always available for cleaning upholstery and the like, a type of work for which the traveling cleaner is unsuitable.
- 60 Thus a single cleaning unit serves for both a hand cleaner and a traveling cleaner and since the unit is complete as to nozzle, motor, dust bag and electrical connections, the change from one type to the other may be accomplished with 65 a minimum of time and effort.
- Having thus described the invention, what is claimed is:
1. A carriage for adapting a hand vacuum cleaner for floor work comprising a support for 70 the cleaner, an axle carried by the support, wheels mounted on the axle, and a handle comprising lengths of wire having their ends partially looped around the axle, the handle having provision for swinging movement limited by engagement of the end faces of the wire with the support.
2. A carriage for adapting a hand vacuum cleaner for floor work comprising a support generally conforming to a part of the cleaner, means for securing the cleaner to the support, an axle carried by the support at the rear portion thereof, the front portion being unsupported to permit the front end of the cleaner to rest upon the floor in close contact with the work, wheels mounted on the axle, and a handle associated with the support for moving the cleaner over 10 the work.
3. A carriage for a hand vacuum cleaner with a generally horizontal motor housing comprising a supporting plate engaging and conforming to the under side of the motor housing, means for securing the motor housing to the plate, an axle, the plate having a rear portion surrounding the axle, wheels carried by the axle, and a handle for operating the cleaner.
4. A carriage for a hand vacuum cleaner with 20 a generally horizontal motor housing comprising a supporting plate engaging and conforming to the under side of the motor housing, means for securing the motor housing to the plate, an axle, the rear portion of the plate flaring outwardly 25 and surrounding the axle, wheels on the axle, and a handle having partially looped end portions surrounding the axle and having its swinging movement limited by engagement with the flared portions of the plate.
5. A carriage for adapting a hand vacuum cleaner for floor work comprising a support for the cleaner, an axle carried by the support, wheels mounted on the axle, a handle comprising a wire yoke having ends partially looped around the 30 axle and twisted wire sections above the yoke, and a cord clip secured between the wires near the upper end.
6. A carriage for adapting a hand vacuum cleaner for floor work comprising a support for the cleaner, an axle carried by the support, wheels mounted on the axle, a handle comprising a wire yoke having ends partially looped around the 35 axle and twisted wire sections above the yoke, a hand grip attached to the upper end of the handle, and securing devices passing between the wires for securing the grip to the handle.
7. A carriage for a hand vacuum cleaner with a cylindrical housing comprising a supporting 40 plate of cylindrical contour to receive the housing, a clamp consisting of a strap hinged to the plate and arranged to embrace the housing, an axle, wheels mounted on the axle, and a handle pivoted to the carriage.
8. A carriage for a hand vacuum cleaner with a cylindrical housing comprising a supporting 45 plate of cylindrical contour to receive the housing, a clamp consisting of strap sections pivoted to opposite edges of the plate to embrace the 50 housing, said sections and plate having cooperating stop devices to limit the outward swinging movement of said sections, the free ends of the sections having securing means for fastening said ends together, an axle, supporting wheels mounted thereon, and a handle for propelling the carriage.
9. In a carriage for a hand vacuum cleaner, a two-part handle comprising a bottom section having two adjacent wires, an upper section of two adjacent wires, a ferrule on one section extending beyond the end thereof to form a socket for the lower end of the other section, the wires of the other section adjacent the lower end being 55

welded, and a screw for securing said other section in the ferrule.

10. A carriage for adapting a hand vacuum cleaner for floor work comprising a support for the cleaner, securing means for securing the cleaner to the support, an axle carried by the support at the rear portion thereof, the front portion being unsupported to permit the front end of the vacuum cleaner to rest upon the floor, 5 wheels mounted on the axle, and a handle on the carriage for moving the cleaner over the work.

11. A carriage for adapting a hand vacuum cleaner for floor work comprising a support for the cleaner, securing means for securing the cleaner to the support, an axle carried by the support at the rear portion thereof, the front portion being unsupported to permit the front end of the vacuum cleaner to rest upon the floor, 10 wheels mounted on the axle, a handle for moving the cleaner over the work, and means for mounting the handle to have provision for limited forward and back swinging movement with respect to the support.

12. A carriage for adapting a hand vacuum

cleaner for floor work comprising a support for the cleaner, securing means for securing the cleaner to the support, an axle carried by the support at the rear portion thereof, the front portion being unsupported to permit the front end 5 of the vacuum cleaner to rest upon the floor, wheels mounted on the axle, and a handle having end portions surrounding the axle on opposite sides of the support.

13. A carriage for a hand vacuum cleaner with 10 a generally horizontal motor housing comprising a supporting plate engaging and conforming to the under side of the motor housing, clamping means for securing the housing to the plate comprising a metallic strap having toggle-operated means for drawing together the ends thereof, non-metallic resilient abutments interposed 15 between the housing and its clamping and supporting means to yield under the compressive action of the strap to permit the toggle-operated 20 means to be moved into locked position, an axle carried by the plate, wheels on the axle, and a handle for operating the cleaner.
